Primary Examiner — George D. Kirschbaum*Assistant Examiner* — Lacey Chey Bowman(74) *Attorney, Agent, or Firm* — Novel Patent Services LLC(57) **CLAIM**

The ornamental design for night vision goggles as shown and described.

DESCRIPTION

FIG. 1 illustrates an isometric view of night vision goggles. FIG. 2 illustrates a front view of the night vision goggles of FIG. 1.

FIG. 3 illustrates a rear view of the night vision goggles of FIG. 1.

FIG. 4 illustrates a right side view of the night vision goggles of FIG. 1.

FIG. 5 illustrates a left side view of the night vision goggles of FIG. 1.

FIG. 6 illustrates a top view of the night vision goggles of FIG. 1; and,

FIG. 7 illustrates a bottom view of the night vision goggles of FIG. 1.

The broken lines shown in the drawings are for the purpose of illustrating portions of the night vision goggles that form no part of the claimed design.

1 Claim, 7 Drawing Sheets(56)
